UNITED STATES PATENT OFFICE

110,193

DESIGN FOR A WAFFLE IRON

Joseph Pavelka, Jr., St. Louis, Mo., assignor to Joseph Pavelka, St. Louis, Mo.

Application March 12, 1938, Serial No. 75,778

Term of patent 7 years

To all whom it may concern:

Be it known that I, Joseph Pavelka, Jr., a citizen of the United States, residing at St. Louis, Missouri, have invented a new, original, and ornamental Design for a Waffle Iron, of which the following is a specification, reference being had to the accompanying drawing, forming part thereof.

I claim:

The ornamental design for a waffle iron substantially as shown.

JOSEPH PAVELKA, JR.
